UNITED STATES PATENT OFFICE.

GEORGE MILLER AYLESWORTH, OF COLLINGWOOD, CANADA.

DESIGN FOR A BUCKLE.

SPECIFICATION forming part of Design No. 23,343, dated June 12, 1894.

Application filed May 15, 1894. Serial No. 511,368. Term of patent 14 years.

To all whom it may concern:

Be it known that I, GEORGE MILLER AYLESWORTH, of Collingwood, Province of Ontario, and Dominion of Canada, have invented a new and original Design for a Buckle, of which the following is a full, clear, and exact specification.

Reference is to be had to the accompanying drawing in which the figure represents a perspective view of a buckle embodying my new design.

The leading feature of my design consists in the buckle having the ornamental design shown, to wit:—the sides *a* presenting essentially ogee figures, the said sides being joined by a series of straight transverse parallel figures *b, c, d, d*, of which the figure *b* appears

at a point centrally of the length of the sides *a*, and presents oppositely disposed protuberances *b'*, the figures *c, c*, next adjacent to the figure *b* joining the sides *a* at points respectively above and below the central figure *b* and at reversely curved portions *a²* of the sides *a*, and the transverse figures *d* joining the terminal ends *a³, a⁵*, of the ogee sides said ends ranging respectively upward and downward from the reverse curves *a²* of the sides.

I claim—

The design for a buckle herein shown and described.

GEORGE MILLER AYLESWORTH.
